TO WESTINGHOUSE LAMP COMPANY, OF BLOOMFIELD, NEW JERSEY, A CORPORATION
OF PENNSYLVANIA.

METALLIC INCANDESCENT FILAMENT

971,452.

Specification of Letters Patent. Patented Sept. 27, 1910.

Application filed August 25, 1906. Serial No. 332,077.

To all whom it may concern:

Be it known that I, ANTON LEDERER, a subject of the Empire of Austria-Hungary, residing at No. 83 Atzgersdorf, near Vienna, in the Province of Lower Austria and Empire of Austria-Hungary, have invented certain new and useful Improvements in Metallic Incandescent Filaments, of which the following is a specification.

10 This invention relates to improvements in metallic incandescence filaments for electric glow lamps, and to a method of treating the same.

In electric glow lamps with metallic filaments, in particular with tungsten (Wolfram) filaments (which burn with an economy of 1 Watt or even less per Hefner candle, and require several filaments for higher voltages) electro-static phenomena 15 occur under certain circumstances. Such filaments become shifted out of their plane, and assume various shapes, and often cross each other although the direction of the current in the contiguous sections is reversed 20 25 so as to have a repelling action.

It is found that filaments in crossing often assume the form of the figure 8 so that by this means not inconsiderable lengths are cut out of circuit.

30 As the separate filaments are almost without mass (a filament of a 4 filament 110 volt 40 candle lamp has a diameter of 0.03 mm. and a weight of 0.002 gram) a slight and possible transient occurrence of statical 35 electrical stress is sufficient to bring it out of its plane. The filament is thus shifted out of its plane may touch the adjacent filament; a portion of the filament is thus cut out of circuit.

40 The present invention relates to an improved form of and method of constructing metallic incandescence filaments for obviating this disadvantage.

It consists in giving both legs of the filament a curvature, an outward curvature having in particular given good results.

The metal filaments can of course have the required form imparted to them before fixing in the glass globe but as the diameter 50 of the entire incandescence structure (consisting of several filaments arranged in a circle) is thereby increased, thus causing difficulties in mounting in the globe, it is of

advantage to impart the requisite shape to the filaments after mounting, either while the globe is being exhausted or when the lamp is completed. The filaments, when already fixed, can be best shaped in the glowing condition, and this can be effected in various ways. Thus sometimes a considerable heating of the lamp is sufficient; or the filaments can be bent by means of permanent magnets or electromagnets or solenoids. The object is also attained by imparting a rapid rotation to the glowing lamp; also, by rubbing the lamp globe preferably with a revolving felt or leather ring, the globe is charged electro-statically and by this means the filaments are attracted and brought into the outwardly curved form. The following 60 method is however to be preferred. The glow lamp is connected to the conductor of an electro-static machine or other source of static electricity, the lamp being preferably surrounded by a metal ring connected 65 to the conductor. The opposite pole of the machine is grounded. When the metal ring is charged the filaments are attracted by or repelled from the glass globe. The lamp is then supplied with current, whereupon the 70 filaments permanently assume an outwardly or inwardly curved form, which will continue more or less even after long use, the outward bulge dropping somewhat lower 75 after a time.

80 In the accompanying drawing, I have illustrated a lamp embodying the features of the invention. The dotted lines S show the symmetrical disposition of the filaments, while the full lines indicated by S' indicate 85 the symmetrical positions into which they have been brought by the means described in the specification.

90 What I claim as my invention, and desire to secure by Letters Patent is:—

1. In an incandescent electric lamp, a central support, a metallic filament having loop-shaped members arranged cylindrically about the support, supports for the ends of the loop-shaped members, anchors engaging the bent portions of the members, the said members being bowed between the supporting ends and the anchors whereby the bent portions are resiliently pressed against their respective anchors.

100 2. In an incandescent electric lamp having

metallic filaments, a central support about which the filaments are cylindrically arranged, the filaments being of loop shape, leading-in wires to which the terminals of 5 the filaments are secured, anchors engaging the looped portions of the filaments, the said filaments being bowed between the supporting ends and the anchors whereby the loops

are resiliently pressed against their respective anchors.

In witness whereof I have hereunto set my hand in presence of two witnesses.

ANTON LEDERER.
